[57] CLAIM

The ornamental design for a golf club head, as shown and described.

DESCRIPTION

FIG. 1 is an elevational view of the rear side of the golf club head embodying my new design;

FIG. 2 is an elevational view of the front side of the golf club head;

FIG. 3 is a top plan view thereof;

FIG. 4 is an end elevational view taken from the right end of FIG. 1;

FIG. 5 is an end elevational view taken from the left end of FIG. 1; and

FIG. 6 is a bottom plan view thereof.
